TRIPOD LEG

Thomas C. Furnas, Jr., Cambridge, Mass.

Application September 9, 1946, Serial No. 695,775

5 Claims. (Cl. 248—178)

1

This invention relates to tripods and more particularly to extensible tripods for supporting cameras, transits, plotting boards, and the like.

Among the several objects of the invention may be noted the provision of a rugged, light-weight, rigid tripod, having a large limit of extension and which when collapsed is of convenient size to carry; the provision of an extensible tripod of the class described which is constructed primarily of standard extruded or rolled metal shapes readily obtainable on the market; and the provision of a tripod of this class which is economical to manufacture. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a side elevation of the tripod standing ready for use but unextended;

Fig. 2 is an enlarged partial plan view of Fig. 1;

Fig. 3 is a cross section taken on line 3—3 of Figs. 1 and 6;

Fig. 4 is a side elevation of a leg hinge and associated parts;

Fig. 5 is a horizontal section taken on line 5—5 of Fig. 4;

Fig. 6 is a detail (partly in section) of a leg clamping device;

Fig. 7 is a view similar to Fig. 4 but viewed from the opposite side;

Fig. 8 is an isometric view of a hinge piece; and,

Fig. 9 is an isometric view of another hinge piece.

Similar reference characters indicate corresponding parts throughout the several views of the drawings.

Many tripods now in use by photographers, surveyors, and others are constructed of wood, insofar as are concerned the telescoping legs. This wood must be of best quality as to grade and seasoning. Even then they tend to warp and stick. Frequently the clamping devices for positioning the legs of wood in tripods are built in such a manner that after continued use the legs become dented and scarred by the clamp which so distorts the shape of the leg that it will not slide freely within its telescoping member. To produce a telescoping tripod of wood requires skill

2

and careful workmanship so that its parts will easily slide within one another.

Metal tripods available in the past have been unsatisfactory because of the use of thin metal sections (in order to reduce the weight) which resulted in limber structures subject to vibration.

By means of the present invention I have overcome these objectionable features of the wooden and metal tripods obtainable heretofore.

Referring now more particularly to Fig. 1, the new tripod consists of three extensible legs 1 each of which is like the other. These are hinged to a base plate 3 at their upper ends. At the lower end of each of the legs 1 is a rubber or other friction-producing foot 5.

The legs 1 are spaced about the base plate 3 at 120° from each other.

The legs 1 are constructed primarily of two aluminum angles 9 between which is slidably mounted a T-shaped aluminum piece 11. These shapes are those readily obtainable in finished form. The material to be used is not necessarily confined to aluminum, and may be, for example, magnesium Duralumin, or the like, all of which are available in standard angle and T-shapes and sizes, and may be obtained without need of further finishing. As shown in the drawing, each angle fits into the angle between the web and part of the head of the T.

Referring to Figs. 4, 5, 7, 8 and 9 each of the angles 9 for one leg has screwed or otherwise secured at the upper end an angled hinge butt 13. This hinge butt fits into the angle 9 snugly and is fabricated from heavier stock than the angle 9.

One wall of the angle 13 is cut away to form a space 15 between it and one web of the angle 9 (see Figs. 7 and 9). The extension 17 formed by the cut-away portion of 13 is provided with a hole 19. A similar hole 21 is also provided in the

adjacent wall of the angle 9. These two holes are located on a common axis. The two identical legs 9 with the hinge pieces 13 are fastened together by a third center hinge-butt piece 23. This third hinge-butt piece is also of a somewhat greater thickness than the material of the legs 9 (see Fig. 8).

One leg 25 of this piece 23 has a hole 27 similar in size to holes 19 and 21 and coaxial therewith. Each other arm 29 of the piece 23 is fastened by screws or the like 31 to one wall of the angles 9, with the holes 19, 21 and 27 aligned.

The leg 25 of the piece 23 is positioned between the other walls of the angles 9 and forms a space 33 between the angles (see Fig. 7). This leg 25 functions as a spacer for the angles 9. The spac-

ing is controlled by the thickness of the part 25. Additional fastening means such as screws 35 are employed at right angles to the screws 31 in order to form a rigid composite hinge-butt for the upper ends of the legs 1.

The resulting five hinge extension portions, constituted by members 17, both upper ends of angles 9, and the spacer 25 are interleaved with four hinge butts 41 of a base hinge piece 43. Three of these base hinge pieces 43 are located 120° apart on the under side of the base plate 3, and are fastened by screws or the like 45. The depending butts 41 are provided with aligned holes 47 and are spaced from each other so as slidably to accommodate the hinge butts of the legs 1 before mentioned.

A hinge pin 49 in each of the three hinges is provided with extending threaded portions at each side to receive tightening wing-nuts 51.

When the legs 1 are spread as shown in Fig. 1 the wing nuts 51 may be tightened to hold the tripod legs in this position; or they may be loosened to permit telescoping of the legs 1 for carrying purposes.

The base plate 3 may be hexagonal in plan or any other desired shape and is provided with holes 53 for mounting an instrument to be supported (not shown).

At the lower extremity, the angle 9 of each leg 1 is held by a channel piece 55 having a cover plate 57 secured to it by screws 59 (see Figs. 1, 3 and 6). These two parts 55 and 57 enclose the two angles 9 and the intermediate T-shaped piece 11. The channel portion 61 of the piece 55 has space between its sides to receive the walls of the two angles 9 and the leg of the T-shaped piece 11 so that the web 63 of the T may slide therethrough.

The cover plate 57 is channeled as at 65 to accommodate the passage of the flange portions 67 of the T-shaped member 11.

A recess 69 is thus provided above and at each side of the channels 61 and in one recess 69 on each leg is pivoted a friction member 71. A portion of the wall of the one angle 9 is cut away as at 73 so that the friction member 71 bears directly against the web 63 of the movable T member 11. The surface of the friction member 71 is likewise cut to fit into the removed portion of the angle 9 and has a portion 75 extending adjacent the wall of angle 9 to a pivot pin 77. This pivot pin confines the friction member 71 within the channel 55 so that it will not be displaced. The pin extends from the channel 55 through the member 71 and into a wall of the angle 9 (see Fig. 3). A threaded wing screw 79 extends through the wall of each channel piece 55 and bears against the friction member 71 opposite the cut-away portion of angle 9. When the wing screw 79 is screwed through the member 55 it presses against the friction member 71 thereby forcing it against the web 63, thereby binding the latter.

At the upper ends of the members 11, guide blocks 81 are screwed to the edges of the webs 63. These overlap the adjacent edges of the angles 9. Thus the members 11 are slidably confined between the walls of the angles 9, that is, in the space 33.

The members 11 can be extended from the legs 1 almost the total length of the members or until the guide blocks 81 abut the channel pieces 55. Thus the total extension of the legs 1 is almost double that of the collapsed condition.

Each T-shaped end member 23 of Fig. 8 forms both a spacing member between the ends of the

L-shaped elongate members 9 and nesting holding means for the ends of these members 9. Likewise, the L-shaped end members 13 are nested into the opposite L-shapes of the members 9 (Fig. 9). Common fasteners hold the assembly together as shown in Fig. 7, with the coaxial openings 19, 21 and 27 all aligned to receive the pivot pins 49. This provides a convenient hinge and spacer construction.

It will be seen from the above that the invention includes the provision of an extensible leg for a tripod or the like which is made up of simple, standard spaced L-shaped elongate members between which is a slidably, standard T-shaped elongate member. Also, the clutch mechanism which is shown in Figs. 3 and 6 is confined within the guide portions attached to the spaced L-shaped members through which slides the confined T-shaped member. This clutch mechanism is not only highly effective, but the internal parts of the clutch mechanism are well guarded. Furthermore, the pivoted flat jaw or clutch portion 71 is highly effective as a clutch, without deforming the web of the T-shaped member where the latter is gripped.

From the above it will be clear that the web of each T-shaped member is indicated at 63, and its flanges are indicated at 67. Each angle member 9 has a web sliding on web 63 and a web sliding on a flange portion 67.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. An extensible leg for tripods and the like comprising an elongate member of T-shape cross section having a central web and lateral flanges, spaced elongate members having L-shaped cross sections which are nested on opposite sides at the first-named member, a part on at least one portion of the web of the T-shaped member confining it between said L-shaped members, surrounding means at the other end of said L-shaped members and spacedly joining them while surrounding and guiding the T-shaped member, a clutch lever pivoted between the surrounding means and one of said L-shaped members and engageable with the web of the T-shaped member, and a screw in the surrounding means and engageable with said clutch lever.

2. An extensible leg for tripods and the like comprising an elongate member of T-shape cross section having a central web and lateral flanges, spaced elongate members having L-shaped cross sections which are nested on opposite sides of the first-named member, the adjacent edges of two spaced webs of the L-shaped members and the edge of the web of the T-shaped member being substantially flush, a head part on at least one portion of the web of the T-shaped member confining it at one end between said L-shaped members, and means confining said L-shaped and T-shaped members at the other end of said L-shaped members.

3. An extensible leg for tripods and the like comprising a pair of elongate L-shaped members having adjacent webs, hinge butt means at one end of said members and determining the spacing between said webs, guide means at the

other end of said L-shaped members arranged also to determine said spacing, a second elongate member of T-section having a web slideable between said spaced webs of the L-shaped members, said second member being slideable through said guide means, a pivoted clutch member confined within said guide means, an adjusting screw threaded through said guide means and engageable and disengageable with said pivoted clutch member, said clutch member being engageable and disengageable with the web of said T-shaped member.

4. An extensible leg for tripods and the like comprising elongate members of L-shaped cross sections, a hinged butt at the upper ends of said members also forming a spacer, a clutch holder at the other end of said members and acting also as a spacer for said L-shaped members, a second elongate member of T-shaped section having its web slideable between webs of the L-shaped members, means attached at one end of said T-shaped member and slidably confining it between said L-shaped members, said T-shaped member passing through the clutch holder at the other end of the L-shaped members, one of said L-shaped members within the clutch holders being recessed to expose a portion of the web of the T-shaped member, a pivoted clutch jaw adjacent

the recess and located within said clutch holder, and means threaded through said clutch holder and operable from the exterior of the clutch holder and cooperating with said clutch jaw.

5. In a leg for tripods and the like comprising two adjacent elongate L-shaped members, a hinge-butt and spacer comprising a T-shaped part, said T-shaped part having a portion functioning as a spacer between the elongate L-shaped members, the ends of said elongate L-shaped members being nested in opposite angles of said T-shaped part, L-shaped hinge-butt parts nested in opposite angles of said L-shaped members, fasteners for holding said members rigidly assembled, and coaxial openings passing through the end portions of the four L-shaped members and the spacing portion of the T-shaped member.
